UNITED STATES PATENT OFFICE

2,596,605

VENTILATOR

Herbert O. Scheller, Nokomis, Ill.

Application December 16, 1949, Serial No. 133,233

2 Claims. (Cl. 20—53)

1

My invention relates to improvements in ventilating windows and the like.

An important object of the invention is to provide a ventilating window particularly well adapted to be installed in sets or groups, to provide adequate ventilation along the entire side of a porch, sun parlor or the like.

A further object is to provide ventilating windows of the above-mentioned character, together with novel and highly simplified operating mechanism for opening and closing a group of the windows in unison.

A further object is to provide windows of the above-mentioned character wherein no frames are needed between the sash of the windows, and accordingly better ventilation and fuller visibility are afforded by the windows, wherever they are installed.

A still further object of my invention is to provide ventilating windows of the above-mentioned character and operating mechanism therefor, the arrangement being highly simplified, compact, strong and durable and relatively inexpensive to manufacture.

Other objects and advantages of the invention will be apparent during the course of the following description.

In the accompanying drawings forming a part of this application, and in which like numerals are employed to designate like parts throughout the same:

Figure 1 is a fragmentary side elevation showing a group of my ventilating windows installed in an opening in the side of a porch or the like;

Figure 2 is a horizontal longitudinal section taken on line 2—2 of Figure 1;

Figure 3 is a vertical section taken on line 3—3 of Figure 1;

Figure 4 is an enlarged fragmentary vertical section taken on line 4—4 of Figure 3;

Figure 5 is a horizontal section taken on line 5—5 of Figure 4;

Figure 6 is a fragmentary perspective view of a window regulator and associated elements;

Figure 7 is an enlarged fragmentary horizontal section taken on line 7—7 of Figure 3;

Figure 8 is an exploded perspective view of a hinge construction employed at the top and bottom of each ventilating window; and

Figure 9 is a fragmentary perspective view of a modified form of ventilator and operating mechanism therefor.

In the drawings, where, for the purpose of illustration, are shown preferred embodiments of my invention, attention is directed first to

2

Figures 1 to 8, inclusive, wherein the numeral 15 designates generally a side of a porch or room provided with a large, rectangular opening 16 extending for substantially the entire length of the side 15, and bounded at its bottom with an elongated, horizontal window sill 17. The top of the large, rectangular opening 16 is bounded by a horizontal, elongated header 18, and the opposite ends of the opening are bounded by vertical frame sides or rails 19.

In order to provide a ventilating closure for the opening 16 which will afford a maximum of visibility, as well as adequate ventilation, I mount within the opening 16 a plurality of vertically elongated, relatively narrow, rectangular window sashes 20. The window sashes 20 are preferably arranged in groups of six, although this number may be varied, and each group of sashes 20 operates in unison for opening and closing the opening 16, as will be more fully described. Of course, if the opening 16 is small enough so that one group of six of the window sashes 20 will be sufficient to completely cover it, only one such group will be employed, and a single group of sashes 20 comprising more or fewer than six sashes may be employed when necessary. In Figures 1 and 2 of the drawings, one group of the window sashes 20 is illustrated for covering the opening 16, and this group comprises the correct number of window sashes, such as six.

Each window sash 20 in the group of window sashes comprises an outer, rectangular frame or sash including top and bottom, horizontal sash members or bars 21 and 22, and sides 23, and 24. No individual frames or vertical separating posts are required between the individual window sashes 20 of the group, and the sides 23 and 24 of each window sash are longitudinally grooved in their inner and outer faces, respectively, as shown at 25 and 26, for forming outer and inner tongues 27 and 28 which interfit with like tongues formed upon the next adjacent window sash. With this arrangement, the sides of adjacent window sashes 20 overlap, as shown in Figure 2, when the window sashes of the group are closed, and no individual window frames are needed.

Adjacent to the top and bottom rails 21 and 22 of each window sash 20, and near the side 24 thereof, dowel plates 29 and 30 are recessed or morticed within the bottom and top faces, respectively, of the header 18 and sill 17. The plates 29 and 30 are thin and rectangular, and are rigidly secured to the header 18 and sill 17 by screws 31 or the like. The plate 29 has a centrally disposed, depending dowel 32 rigidly se-

cured to its bottom face and projecting below the bottom face of the top rail 18. The plate 30 has a similar upstanding dowel 33 rigidly secured to its top face and projecting above the top face of the window sill 17. The dowels 32 and 33 are arranged in vertical alignment. Recessed or morticed within the top and bottom faces, respectively, of the bars 21 and 22 of each window sash 20 are elongated, rectangular hinge plates 34 rigidly secured to the bars 21 and 22 by means of screws 35 or the like. The hinge plates 34 are provided with central openings 36 receiving therein the dowel pins 32 and 33. Brass washers or thrust bearings 37 are mounted upon the pins 32 and 33 and arranged between the pairs of plates 29 and 34 and 30 and 34, to facilitate the free horizontal swinging movement of the sashes 20 when the same are opened and closed. The hinge plates 34 are flush with the top and bottom edges of the window sashes 20, and adapted to swing freely adjacent to the bottom face of the header 18 and the top face of the sill 17, respectively. Each hinge plate 34 has an integral, laterally inwardly projecting, inclined extension or arm 38 having an aperture 39 in its inner end for receiving a pivot pin 40, pivotally connecting the arms 38 of the hinge plates with a common, longitudinally extending, horizontal, elongated, connecting rod 41 extending adjacent to the inner sides of the window sashes 20 at the tops and bottoms of the window sashes. The connecting rods 41 at the tops and bottoms of the window sashes 20 thus serve to operatively connect the window sashes of the group together through their arms 38, so that they may be opened and closed in unison.

The bottom connecting rod 41, only, adjacent to one end thereof is pivotally connected with an intermediate, relatively short, horizontally swingable connecting rod or link 42 arranged above the window sill 17 inwardly of the sashes 20, and in turn pivotally connected at its opposite end, as shown at 43, with one end of a horizontally swingable crank arm 44 having its opposite and inner end pivotally connected, as at 45, with the top end of a vertically disposed shaft 46 projecting through the top of a small, rectangular housing or regulator casing 47 rigidly mounted upon the top face of the window sill 17 adjacent to one end sash 20 in the group of sashes. The shaft 46 extends vertically through the housing 47 and has a gear 48 mounted thereon and arranged within the housing for rotation therewith. This gear 48 meshes with and is driven by a worm gear 49 secured to a horizontally disposed shaft 50 projecting through the rear vertical side of the housing or casing 47 for connection with a crank handle 51 which is operable for driving the gears 48 and 49 to swing the arm 44 horizontally in both directions. By operating the crank 51, it is thus possible through the crank arm 44, link 42 and elongated connecting rod 41 at the bottom of the windows to open and close the sashes 20 of the group in unison. By virtue of the additional connection between the sashes 20 at their tops through the medium of the top connecting rod 41 and associated elements, the sashes 20 of the group are connected in a very strong and durable manner. Accordingly, forces, such as those exerted by the wind, will not tend to spring or otherwise damage the sashes or their hinged connections with the header 18 and sill 17. With the arrangement provided, it is possible to open the sashes 20 of the group until they are arranged substantially at right angles to the sides 15 of the porch, and in this position the

opening 16 will be substantially entirely uncovered for affording maximum ventilation and visibility. As previously stated, there are no individual window frames or uprights between the adjacent sashes 20 of the group.

In Figure 9, I have shown a slight modification of my invention, wherein elongated or taller sashes or ventilators 52 are provided, and these sashes or ventilators 52 are preferably of the height of doors generally employed upon a house. It may be desirable to install groups of the sashes or ventilators 52 upon opposite sides of a door at one end of a room or porch. Such groups of the ventilators 52 are to be operated simultaneously, generally in the manner that the sashes 20 of the first form of the invention are operated. Two or more of the ventilators 52 may accordingly be connected or coupled together for simultaneous operation in generally the same manner that the sashes 20 are connected for simultaneous operation.

In the form of the invention shown in Figure 9, a lower floor level sill or rail 53 is provided, and this rail 53 receives the lower dowel plate 30, carrying the lower upstanding dowel pin 33. The plate 30 is flush with the top face of the rail 53. The upper dowel plate 29, not shown, is mounted in a suitable header in exactly the same manner that the dowel plate 29 is mounted upon the header 18 in the first form of the invention. Likewise, one hinge plate 34 is mounted flush with the top bar 54 of the ventilator 52 and the bottom hinge plate 34 is secured to the bottom bar 55 of the ventilator 52 in the identical manner in which the plate 34 is secured to the bottom bar 22 of the sash 20. The ventilators 52 are substantially taller than the sashes 20, and accordingly, a fixed, elongated, horizontal rail 56 is provided near the vertical centers of the ventilators 52 and provided in their outer sides with arcuate notches 57, forming clearance for the inner sides of the ventilators 52 to swing through. The regulator casing 47 is mounted upon the intermediate horizontal rail 56, adjacent to the end ventilators 52 of the group. The regulator for opening and closing the ventilators 52 is substantially identical with the regulator for opening and closing the sashes 20, except that the vertically disposed shaft carrying the gear 48 is elongated vertically and extends above and below the regulator and above and below the intermediate rail 56, as shown at 46'. The same crank handle 51 is provided, as in the first form of the invention, for operating the regulator to impart rotation to the vertical, elongated shaft 46'. The shaft 46' extends adjacent to the top and bottom edges of the ventilators 52 and has rigidly secured, as by welding, to its top and bottom ends horizontally swingable crank arms 58. Pivotally connected, as at 59, with the free ends of the crank arms 58, are intermediate, horizontally swingable links or rods 60. The opposite ends of the links 60 are pivotally connected, as at 61, with the adjacent ends of the top and bottom elongated, horizontal connecting rods 41. These connecting rods 41 are disposed adjacent to the top and bottom edges of the ventilators 52 in the same manner that they are disposed adjacent to the top and bottom edges of the sashes 20. The inwardly or rearwardly extending horizontal arms 38 of the hinge plates 34 are pivotally connected, as at 62, with the top and bottom connecting rods 41 at longitudinally spaced intervals along the connecting rods. Accordingly, the ventilators 52 are swung horizontally from opened to closed positions by

the operation of the cranks 51 in the same manner that the sashes 20 of the first form of the invention are operated. However, in the form of the invention shown in Figure 9, the elongated, vertical shaft 46, crank arms 58 and associated elements are operatively connected with the ventilators 52 at both their top and bottom ends, so that the opening and closing effort is applied to the ventilators 52 at their top and bottom ends. This is a stronger construction and is necessitated by the fact that the ventilators 52 are substantially longer or taller than the sashes 20. Otherwise, there is substantially no difference between the construction or operation of the ventilators 52 and sashes 20. Both arrangements are simplified, compact and very strong and durable.

It is to be understood that the forms of my invention herewith shown and described are to be taken as preferred examples of the same, and that various changes in shape, size and arrangement of parts may be resorted to without departing from the spirit of my invention or the scope of the subjoined claims.

Having thus described my invention, I claim:

1. A ventilating closure for a side wall having an opening bounded by a header and a sill comprising at least one pair of flat dowel plates positioned in spaced relation along the under face of said header and fixedly secured to the latter, a dowel pin depending from each one of said pair of dowel plates, at least a second pair of flat dowel plates positioned in spaced relation along the upper face of said sill and secured to the latter, an upstanding dowel pin projecting from each one of said second pair of dowel plates, the dowel pins of said one pair of dowel plates being in alignment with the dowel pins of said second pair of dowel plates, at least two window sashes arranged in side by side abutting relation positioned longitudinally of and within said opening, a flat hinge plate fixedly secured to the upper face of each of said sashes intermediate the sides thereof and each loosely receiving the depending dowel pin adjacent thereto, a second flat hinge plate fixedly secured to the under face of each of said sashes intermediate the sides thereof and each loosely receiving the upstanding dowel pin adjacent thereto, an arm arranged transversely of each of said first and second named hinge plates and having one end secured to the latter, a horizontally disposed rod arranged longitudinally of said header and said sill adjacent the other ends of the arms of said first and second named hinge plates and pivotally connected to the other ends of said arms adjacent thereto, a link arranged longitudinally of the rod contiguous to said sill adjacent one end of the latter named rod and having one end pivotally connected to said one rod end, and a manually actuatable regulator mounted on said sill adjacent said one end of the rod contiguous to said sill and operatively connected to the other end of said link for opening and closing the sashes in unison.

cent thereto, and a manually actuatable regulator positioned on said sill adjacent one end of the rod contiguous to said sill and operatively connected to the latter named rod for opening and closing the sashes in unison.

2. A ventilating closure for a side wall having an opening bounded by a header and a sill comprising at least one pair of flat dowel plates positioned in spaced relation along the under face of said header and fixedly secured to the latter, a dowel pin depending from each one of said pair of dowel plates, at least a second pair of flat dowel plates positioned in spaced relation along the upper face of said sill and secured to the latter, an upstanding dowel pin projecting from each one of said second pair of dowel plates, the dowel pins of said one pair of dowel plates being in alignment with the dowel pins of said second pair of dowel plates, at least two window sashes arranged in side by side abutting relation positioned longitudinally of and within said opening, a flat hinge plate fixedly secured to the upper face of each of said sashes intermediate the sides thereof and each loosely receiving the depending dowel pin adjacent thereto, a second flat hinge plate fixedly secured to the under face of each of said sashes intermediate the sides thereof and each loosely receiving the upstanding dowel pin adjacent thereto, an arm arranged transversely of each of said first and second named hinge plates and having one end secured to the latter, a horizontally disposed rod arranged longitudinally of said header and said sill adjacent the other ends of the arms of said first and second named hinge plates and pivotally connected to the other ends of said arms adjacent thereto, a link arranged longitudinally of the rod contiguous to said sill adjacent one end of the latter named rod and having one end pivotally connected to said one rod end, and a manually actuatable regulator mounted on said sill adjacent said one end of the rod contiguous to said sill and operatively connected to the other end of said link for opening and closing the sashes in unison.

HERBERT O. SCHELLER.
